EQUALIZER DAMPENING MEANS FOR RAILWAY CAR TRUCKS

Claude L. Orr, Columbus, Ohio, assignor to The Buckeye Steel Castings Company, Columbus, Ohio

Application March 15, 1939, Serial No. 262,022

11 Claims. (Cl. 105—183)

This invention relates to improvements in railway car trucks and more particularly to equalizer dampening means for eight-wheel trucks.

5 In eight-wheel trucks of the equalizer type, I have considered the question of excessive equalizer oscillations under extremely rough track conditions. Such oscillations may cause excess wear at the equalizer fulcrum pin and 10 the end frame connections, as well as contribute to the oscillation of the spring groups in the end frame members.

15 The tendency for the equalizer to oscillate excessively will increase as wear between the connections reduce the friction at these points, and in order to meet this situation, should the case arise, I have developed certain novel constructions for the purpose of dampening the equalizing action.

20 Other, further and more specific objects of my invention will become readily apparent to persons skilled in the art, from a consideration of the following description when taken in conjunction with the drawings, wherein—

25 Fig. 1 is a side elevation of one-half of an eight wheel truck provided with one form of my improvements, it being understood that the other half of the truck is exactly the same as the half illustrated.

30 Fig. 2 is a side elevation of the medial portion of such a truck and showing other forms of my improvements.

Fig. 3 is a plan view of a leaf spring employed in the construction illustrated in Fig. 2.

35 Fig. 4 is a side elevation of a fragment of a truck and illustrating a leaf spring type of oscillation damper.

Fig. 5 is a view similar to Fig. 4 but showing a block of rubber or the like employed for 40 dampening purposes.

Fig. 6 is a top plan view of the structure shown in Fig. 5.

Fig. 7 is also a top plan view of another form of the invention.

45 Fig. 8 is a side elevation partly in elevation of the structure shown in Fig. 7.

Figs. 9 and 10 are views similar to Figs. 7 and 8 but illustrating a still further modification.

50 The truck with which I employ my improvements may be of the type disclosed in my application, Serial No. 197,927. Such a truck has eight wheels 11 carrying axles (not shown) journalled in boxes 12 and 13. End frame members 14 are carried partially by the boxes 12 and 45 55 60 65 70 75 80 85 90 95 98 99 100 101 102 103 104 105 106 107 108 109 110 111 112 113 114 115 116 117 118 119 120 121 122 123 124 resists the sliding action of the spring on the pads.

Rotation of the equalizer in either direction causes the lug 26 to contact one side of the hole 25 and slide the ends of the spring over the pads 27 against the friction force developed there. The resistance offered by this friction serves to resist the equalizer motion and dampens its oscillations.

Fig. 4 shows a modification similar to that at 10 the ends of the equalizer in Fig. 2. In this embodiment a leaf spring 28 has one of its ends secured to a bracket 29 on the equalizer 16b, and its end portion bears at its top surface against an arc-shaped portion 30 arranged at the end of 15 a horn 31 rigidly united with an end frame member 14b of the truck.

In the embodiment of the invention illustrated in Figs. 5 and 6, a block 32 of rubber or the like is supported above the equalizer and end frame 20 connection 15c by means of brackets 33 and 34 provided respectively on the tops of the end frame member 14c and equalizer 16c. Lugs 35 on the brackets project toward one another and extend into the block. The latter is applied to 25 one of the brackets before the end frame member and equalizer are connected and held in proper alignment with the lug 35 on the other bracket as the frame member and equalizer are moved together and connected by the equalizer 30 bolt 15c. Of course, a similar construction is used at the opposite end of the equalizer.

When the equalizer rotates out of horizontal position, the lugs 35 move vertically relative to one another thereby subjecting the rubber blocks 33 at both ends to vertical shearing deformations.

At the downwardly moving end of the equalizer, the brackets 33 and 34 move toward each other, thereby subjecting the elastic block at this end to a horizontal compressible deformation. 40 At the upwardly moving end, the brackets move away from each other and would subject the rubber block at that end to a horizontal tensile deformation if it were secured to the vertical faces of the brackets. This, however, is not contemplated, and this tensile deformation can not be depended upon to resist the equalizer movements.

Since rubber is a highly resilient material, the forces set up in the rubber block by the shearing 50 and compressive deformations resist the equalizer movement and tend to dampen excessive oscillation.

Figs. 7 to 10 inclusive, illustrate other dampening devices in which the resilient material is rubber or the like. In the form of the invention illustrated in Figs. 7 and 8, the inner end portion of the side frame member 14d is provided with a hole 15d of larger diameter than the bolt 15e employed in connecting the same to the equalizer 60 member 16d, and the end of the side frame member terminates in a substantially vertical surface 36. This surface cooperates with a block 37 of rubber which is set in a pocket 38 in an end portion of the equalizer member 16d. Wear or 65 protector plates 39 are provided at opposite sides of the block and the block and plates are protected by a cover plate 40, which may be welded to the equalizer member as indicated at 41. When the equalizer member rotates about its fulcrum pin (corresponding to the fulcrum pin 17 in Fig. 1), the space between the extremity 36 of the side frame and the back wall of the pocket 38 decreases at the downwardly moving end and increases at the upwardly moving end. The 70 equalizer connection bolt hole 15d being larger 75

than the bolt accommodates this relatively horizontal motion between the members and as a rubber block 37 of proper thickness is arranged in the space between the two members at each end of the equalizer and, since this block is compressed at one end or the other of the equalizer when the member rotates, it serves to dampen the equalizer movement.

The plates 39 provide metal bearing surfaces 10 for contacting the end frame equalizer members and also serve to distribute the pressure exerted by the members uniformly over the rubber block. The structure shown in Figs. 9 and 10 is similar to that illustrated in Figs. 7 and 8 with the exception that I make the top plate 42 integral with 15 the wear plate 43 and secure the composite plate in position by welding at 44.

Obviously the plates 40 and 42 serve to protect 20 the rubber block from weather, foreign objects, etc.

When used in a truck of the type disclosed in my application Serial No. 197,927, the rubber blocks also assist in propelling the intermediate portion of the truck, which consists of the equalizer, intermediate frame, and the two intermediate 25 axles and their wheels, thereby reducing the forces which are transmitted through the bolts, which connect the end frame members to the equalizer member.

Many modifications of the invention will be 30 apparent to those skilled in the art without departing therefrom or from the scope of the claims, and since the foregoing disclosure has been given by way of examples for clearness and understanding, no unnecessary limitations should 35 be understood and the appended claims should be construed as broadly as the state of the art permits.

What I claim and desire to secure by Letters 40 Patent is:

1. In a car truck, a wheel-supported intermediate side frame member, an oscillatable equalizer member carried by said side frame member, end frame members movably connected to the ends of the equalizer member, and means 45 for dampening oscillations of the equalizer member.

2. In a car truck, a wheel-supported intermediate side frame member, an oscillatable equalizer member carried by said side frame member, end frame members movably connected to the ends of the equalizer member, and means 50 for dampening oscillations of the equalizer member, said means comprising an elastic element carried by one member and bearing against 55 a part rigidly united with another one of the members.

3. In a car truck, a wheel-supported intermediate side frame member, an oscillatable equalizer member carried by said side frame member, end frame members movably connected to the ends of the equalizer member, and means 60 for dampening oscillations of the equalizer member, said means comprising a metallic spring carried by one of the members, and a projection 65 rigidly united with another one of the members and engaging said spring.

4. In a car truck, a wheel-supported intermediate side frame member, an oscillatable equalizer member carried by said side frame member, end frame members movably connected to the ends of the equalizer member, and means 70 for dampening oscillations of the equalizer member, said means comprising a metallic spring secured to an end portion of one of the mem- 75

bers and having a free end bearing against an end portion of another one of the members.

5. In a car truck, a wheel-supported intermediate side frame member, an oscillatable equalizer member carried by said side frame member, end frame members movably connected to the ends of the equalizer member, and means for dampening oscillations of the equalizer member, said means comprising a leaf spring having one of its ends secured to one of said members and bearing at its opposite end against an end portion of the other member.

6. In a car truck, a wheel-supported intermediate side frame member, an oscillatable equalizer member carried by said side frame member, end frame members movably connected to the ends of the equalizer member, and means for dampening oscillations of the equalizer member, said means comprising a block of resilient material.

7. In a car truck, a wheel-supported intermediate side frame member, an oscillatable equalizer member carried by said side frame member, end frame members movably connected to the ends of the equalizer member, and means for dampening oscillations of the equalizer member, said means comprising abutment surfaces arranged upon adjacent ends of the equalizer member and one of the end frame members, and a block of resilient material arranged between said surfaces.

8. In a car truck, a wheel-supported intermediate side frame member, an oscillatable equalizer member carried by said side frame member, end frame members movably connected to the ends of the equalizer member, and means for dampening oscillations of the equalizer member, said means comprising a resilient

block arranged between the inner extremity of one of the side frame members and an end portion of the equalizer member.

9. In a car truck, a wheel-supported intermediate side frame member, an oscillatable equalizer member carried by said side frame member, end frame members movably connected to the ends of the equalizer member, and means for dampening oscillations of the equalizer member, said means comprising a resilient block arranged between the inner extremity of one of the side frame members and an end portion of the equalizer member, and a protecting cover plate for said block secured to the equalizer member.

10. In a car truck, a wheel-supported intermediate side frame member, an oscillatable equalizer member carried by said side frame member, end frame members movably connected to the ends of the equalizer member, and means for dampening oscillations of the equalizer member, said means comprising a resilient block arranged between the inner extremity of one of the end frame members and an end portion of the equalizer member, metallic plates arranged at opposite sides of the block, and means forming a cover for the block.

11. In a car truck, an intermediate side frame member, an oscillatable equalizer member pivotally supported at its medial portion by the medial portion of said side frame member for movement about a horizontal axis, end frame members having their inner ends movably connected to the ends of the equalizer member, and means for dampening oscillations of the equalizer member.

CLAUDE L. ORR.
